(57) **CLAIM**

The ornamental design for an optical fiber management cassette, as shown and described.

DESCRIPTION

This application is related to co-pending design patent application Ser. No. 29/426,354, entitled “Optical Fiber Management Bracket” filed on Jul. 3, 2012, and to non-provisional patent application Ser. No. 13/541,419, entitled “Optical Fiber Connectivity Management System” also filed on Jul. 3, 2012.

FIG. 1 is a perspective view of an optical fiber management cassette showing our new design;

FIG. 2 is a front elevation view thereof;

FIG. 3 is a side elevation view thereof; and,

FIG. 4 is a bottom plan view thereof.
